TRIP MECHANISM FOR POWER SHOVELS

James H. Edwards, Village of Welland Junction,
Ontario, Canada

Application March 28, 1946, Serial No. 657,845

3 Claims. (Cl. 214—146)

1

The invention relates to improvements in trip mechanisms for power shovels which are devised to utilize a rotating member of the hoisting mechanism for tripping the bottom or door of the bucket or dipper.

The major object of the invention is to provide a semi-automatic trip of the kind referred to which is devised to reduce to minimum the effort required by the operator in tripping the bucket for release of the load.

Another object is to provide a trip mechanism which facilitates and expedites the operation of the excavating machine.

The conventional trip cable of such a machine demands considerable effort on the part of the operator in order to unlatch the door of the dipper in the dumping operation. My invention is of the semi-automatic type and comprises a drawbar having a friction face and being slidably mounted on a carriage swingably suspended and manually operated by a counter-balanced hand-lever. The drawbar is attached to the trip cable and its friction face is brought into engagement with the revolving hoist drum in order to pull the trip cable. Means are provided in the nature of a take-up or compensating device for keeping the trip cable taut in positional movements of the dipper handle.

A selected embodiment of the invention is shown in the accompanying drawing, in which:

Fig. 1 is a side elevation partly in section of a power shovel embodying the improved trip mechanism.

Fig. 2 is a fragmentary axial section of the hoisting drum showing how the drawbar engages an annular surface thereof.

Fig. 3 is a longitudinal section of the drawbar and the supporting carriage.

Fig. 4 is a perspective view of the drawbar showing the friction face thereof.

Fig. 5 is a top plan view of the carriage.

Fig. 6 is a cross section thereof taken on line 6—6 of Fig. 5.

Fig. 7 is a perspective view of the dipper or bucket viewed from its bottom side to depict the latch mechanism thereof.

Fig. 8 is a front elevation of the trip mechanism including the control lever but omitting the annular element of the hoisting drum by which the drawbar is actuated.

Fig. 9 is a cross section on line 9—9 of Fig. 1 depicting the pulley take-up device on the boom for the drawbar-cable.

The trip mechanism of this invention is associated with the regular hoisting drum, repre-

2

sented by the reference character 10. This drum operates the hoisting cable 11 for elevating and lowering the dipper or bucket 12. The mechanism, such as the gearing, clutch and brake, for operative control of said drum is not shown in the drawing for the reason that it does not form a part of the invention. It will be understood, however, by those familiar with such excavating machines that the drum is connected by conventional mechanism to an engine in the swing body or cab 13. The traction base of the swing body is indicated at 14, and the usual boom or beam is denoted at 15, on which is mounted the dipper handle 16. The rack teeth 17 of the handle are engaged by ordinary gear mechanism (not shown) for crowding out and racking operations. This mechanism includes a shaft 18 journaled on the boom. This shaft is only driven during racking in and racking out operations of the handle and its direction of rotation depends on whether the dipper is being fed outwardly or inwardly of the boom.

In carrying out the present invention, the shaft 18 is employed for the operation of a take-up or compensating device for the trip cable, as will be later described.

The invention comprises a drawbar 19 in the form of a flat-sided elongated member which is arranged above the hoisting drum 10 and connected to an end of a flexible element 20 which extends from the latch mechanism of the bottom or door 21 of the bucket or dipper 12. The flexible element is a cable or trip rope which is pulled to unlatch said bottom or door to discharge the contents of the bucket.

The drawbar is endwise slidable in a carriage or carrier 22 at the underside thereof by an arrangement of roller bearings, as at 23. On the drawbar there is provided a comparatively short strip of brake lining 24 or a comparable material such as to provide a friction face on the lower side of the drawbar. The brake lining is rigidly applied as by soft metal rivets. The lining is disposed to be engaged with an annular friction face on the drum 10, which may be supplied by a ring or the like as at 25 integral with or secured to the drum.

The carriage is swingable to and away from the drum, and has its inner end pivoted or hinged at 26 to a bar 26' or the like, which is fixedly supported in the cab 13. The free end of the carriage is supported by a control mechanism comprising a crank pivoted at 27 to a connecting bar 28 which in turn is pivoted at 29 to the carriage. The crank is composed of a shaft 30

horizontally journaled at 31 in the cab, and an arm 31 by which said crank is pivoted to the bar 28. On the crank is a counterweight 32 which balances the combined weight of the carriage and the drawbar. The carriage is manually controlled by a handlever 33 rigid with the crank and disposed conveniently to the operator within the cab.

In the operation of the machine, the drum 10 is rotated anti-clockwise to hoist the loaded bucket for dumping the load into a motor truck or the like. To open the door 21 of the bucket the operator pulls the lever 33 in order to lower the carriage so that the friction lining of the drawbar will make contact with the ring 25 of the revolving drum. The friction contact functions to forcibly retract the drawbar, thus pulling on the flexible element 20 and releasing the latch of the bucket. In the pulling operation the friction lining rides off the ring of the drum and automatically disengages the drawbar. A stop piece 34 limits the inward travel of the drawbar and is engaged by a buffer 35 which desirably consists of a block of rubber mounted on the inner end of the drawbar. The friction lining or pad is made of a length merely sufficient to cause the latch mechanism to have the necessary withdrawal movement and following this movement the operator pushes the lever 33 to raise the carriage to a normal position in which the friction lining will not contact the drum-ring on the return movement of the drawbar, which is self-returning by reason of the pull exerted on the flexible element by the door of the bucket.

The latch mechanism preferably comprises a pair of levers of which the lever 36 is pivoted at 37 to the bottom or door 21 of the bucket and arranged transversely of the spring-projected latch bar 38 to which it is pivoted at 39. The other lever, denoted at 40, is arranged transversely of the boom 16 and pivoted at an end at 41 thereto. The other end has a swivel connection 42 with a pulley 43 and is limited as to its swing by means of an element 44. The levers 36 and 40 are connected one to the other by a chain 45. By this arrangement, movement of the lever 40 outwardly of the bucket serves to withdraw the latch bar 38.

In order to keep the trip cable 20, normally taut irrespective of positional movement of the bucket, there is provided a take-up or compensating device comprising the grooved pulleys 46 and 47. The pulley 46 is loosely mounted on the shaft 18 aforesaid and the pulley 47 is fixedly mounted on this shaft for rotation therewith and is of a comparatively large diameter. The cable 20 is trained over the loose pulley 46 and the pulley 43. The outer cable end 48 is attached to the pulley 47 for winding and unwinding thereon. An idler pulley 49 on the boom is used to guide the inner end or stretch of this cable.

Since the pulley 47 is fixed on the shaft 18, it is turned according to the direction of endwise movement of the dipper handle 16 and in proportion to such movement with the result that the trip cable is either wound on the pulley 47 or unwound therefrom in order to take up any slack or to pay out the cable to maintain it taut.

It will be manifest that the invention provides a semi-automatic trip mechanism which not only requires but little manual effort to operate, but is also a time-saving appliance.

5 What I claim is:

1. In excavating mechanism of the class described, the combination with dipper door latch mechanism and a hoisting cable drum, of instrumentalities for operating the latch mechanism by utilizing the drum as a source of power comprising an annular friction face provided on the drum, a trip cable, a drawbar connected to the trip cable having a friction face for engaging that of the drum in order to pull the trip cable in an operational movement, a carriage supporting the drawbar for endwise movement and mounted for transversely shifting the drawbar to engage the friction face thereof with that of the drum, a hand lever for operating the carriage, and a buffer on the drawbar for limiting the travel thereof in pulling the trip cable.

2. In excavating mechanism of the class described, the combination with dipper door latch mechanism and a hoisting cable drum, of instrumentalities for operating the latch mechanism by utilizing the drum as a source of power comprising means providing an annular friction face rotatable with said drum, a trip cable, a drawbar connected to the trip cable having a friction face for engaging said annular friction face, and means for reciprocably supporting the drawbar and for transversely shifting it for engagement of its friction face with said annular friction face, said means including a hand control, the structure being characterized in that the friction face of the drawbar is provided by a pad or strip of material such as brake lining of a length such that it will ride off said annular friction face when the necessary pull has been imparted to the trip cable, whereby to automatically sever the engagement of said friction faces.

3. In a power shovel, a dipper provided with a door, a latch mechanism for holding the door closed including a lever carrying a pulley, a dipper handle having rack teeth, gear means engaged with said rack teeth for crowding out and racking in operations, the gear means including a shaft, a pair of grooved pulleys mounted on the shaft, one of the pulleys being a loose pulley and the other a tight pulley, a trip cable having an inner end and an outer end, the cable being trained over said loose pulley and the pulley on said lever with its outer end connected to the tight pulley, and a semi-automatic tripping device connected to the inner end of the cable.
